PAPERBOARD SERVING TRAY

Earl P. Buchmiller and Harold Cohen,
Denver, Colo.

Application January 16, 1952, Serial No. 266,648

4 Claims. (Cl. 229—27)

1

This invention relates to trays for the handling and serving of foods, drinks, and analogous products, and more particularly to such trays as adapted to facilitate customer service at theaters, stadiums, snack bars, "drive-in" restaurants, picnics, and the like, and has as an object to provide a novel, efficient, and inexpensive folded paperboard construction for such trays.

A further object of the invention is to provide an improved folded paperboard serving tray construction characterized by an initial sheet blank highly conservative of stock material.

A further object of the invention is to provide an improved folded paperboard serving tray construction characterized by self-locks eliminative of all occasion for stitching, stapling, gluing, pasting, or analogous assembly operations.

A further object of the invention is to provide an improved folded paperboard serving tray construction adapted for production, transportation, and storage in flat sheet form.

A further object of the invention is to provide an improved folded paperboard serving tray adapted for production in flat sheet form and susceptible of erection into form for use without recourse to agencies, tools, or instrumentalities other than the human hands.

A further object of the invention is to provide an improved folded paperboard serving tray adapted for such economy of production as to be expendable.

With the foregoing and other objects in view, our invention consists in the construction, arrangement, and combination of elements as herein-after set forth, pointed out in our claims, and illustrated by the accompanying drawings, in which—

Figure 1 is a top plan view of one preferred embodiment of the invention as constructed and erected ready for practical use. Figure 2 is a side elevation of the tray shown in Figure 1. Figure 3 is a cross section taken substantially on the indicated line 3—3 of Figure 1. Figure 4 is a fragmentary, detail section taken substantially on the indicated line 4—4 of Figure 2. Figure 5 is a plan view, on a reduced scale, of the sheet blank primary to the tray as shown in the preceding views. Figure 6 is a top plan view of an alternative embodiment of the invention in condition for practical use. Figure 7 is a side elevation of the tray shown in Figure 6. Figure 8 is a fragmentary, detail section, on a relatively enlarged scale, taken substantially on the indicated line 8—8 of Figure 6. Figure 9 is

5 a fragmentary, detail section, on the same scale as Figure 8, taken substantially on the indicated line 9—9 of Figure 7. Figure 10 is a plan view, on a reduced scale, of the sheet blank primary to the tray as shown in Figures 6—9, inclusive.

The serving tray represented by Figures 1—5, inclusive, is evolved in form for practical use from an initially-flat, substantially-rectangular, appropriately scored and incised sheet of paperboard, or analogous material, through interfolding and interlocking of elements to which the sheet is patterned, and in such practical use form the tray combines an open-top compartment of about one-half the tray area adapted to accommodate solid foods with a boxed or covered complementary tray area conditioned for the support and reception of beverage containers in and as a unit assembly particularly adapted for the serving of one or two customers. Primary to 10 and including all of the elements for the practical use form of the tray in its simpler embodiment, the unitary sheet blank represented by Figure 5 is cut and worked to the form and arrangement of elements hereinafter detailed, and to any preferred element size and proportion, from stock sheets or rolls of suitable paperboard, or similar material, through the agency of known and available means and the application of conventional techniques, preferably and expeditiously in a single operation.

In a rectangular outline modified as herein-after set forth, the sheet blank shown in Figure 5 is developed with parallel long side margins in a width equalling the desired tray width plus twice the desired tray depth and with parallel end margins perpendicular to its long side margins determining a blank length on the order of, and slightly exceeding, one and one-half times the desired tray length plus four times the desired tray depth. Paralleling the blank long side margins and similarly spaced inwardly from each thereof a distance corresponding with the desired tray depth, an aligned succession of incisions and fold line scorings sets off a like side area laterally of and along a longitudinally central blank area having a width corresponding with that of the desired tray. Each of said successions of incisions and fold line scorings is constituted as a first incised section 15 extending inwardly and longitudinally of the blank a distance equal to twice the desired tray depth, a scored fold line section 16 aligned with the incised section 15 and extending thence longitudinally of the blank a distance equal to the desired tray length, a second incised section 17 aligned

with and extending longitudinally of the blank from the section 16 a distance approximately twice the desired tray depth, a scored fold line section 18 aligned with and extending longitudinally of the blank from the junction of the sections 16 and 17 a distance equaling approximately one-half the desired tray length as represented by said section 16 plus the desired tray depth, and a final incised section 19 aligned with and extending longitudinally of the blank from said section 18 through the adjacent end of the blank, each of said final incised sections 19 being interrupted, or offset, at its approximate midlength to form a tab 20 outstanding laterally of the blank a short distance beyond each of the just-described aligned succession of incisions and fold line scorings. On the free end of the blank longitudinally central area embraced between the incised sections 15 short tabs 21 are formed to spacedly interrupt and outstand beyond the blank end and a scored fold line 22 transversely of and extending entirely across the blank at the junction of the incised sections 15 and scored line sections 16 includes slits 23 cut through the blank material in alignment longitudinally of the blank with the tabs 21 for interlocking cooperation with the latter, as will hereinafter appear. The scored line 22 demarks an end section of the blank longitudinally central area between the incised sections 15 which is further bisected by a scored fold line 24 spanning between said incised sections 15 in parallel with the line 22 and adjacent end of the blank, thus to define like, contiguous tray end panels 25 and 26 foldable into superposition and into perpendicular relation with the original plane of the blank in a uniformity of length equal to the desired tray width and a uniformity of width corresponding to the desired tray depth, and extensions of the scored line 22 laterally of the blank beyond the incised sections 15 and to the blank side margins define flaps 27 at the corresponding ends of the blank side strips, which flaps are hence foldable into perpendicular relation with the areas which they terminate. Spacedly paralleling the scored line 22, a scored fold line 28 traverses the entire width of the blank at the junctions of the scored line sections 16 and incised sections 17 to delimit, in cooperation with the said line 22 and sections 16, a rectangular, generally-central, blank area 29 sized to the width and length dimensions desired for the tray and adapted to function as the tray bottom, extensions of the scored line 28 across and laterally of the blank side strips cooperating with the corresponding line 22 extensions to delimit side strip panels 30 oppositely bounding the area 29 and foldable into perpendicular relation with the latter as tray side walls. At the junctions of the incised sections 17 with the scored line sections 18, incisions 31 laterally interrupt the blank side strips to free the ends of side strip flaps 32, identical with the flaps 27 save for location, thus conditioned for folding at the line 28 extensions into perpendicular relation with the panels 30 which they terminate. Paralleling the scored line 28 and spaced therefrom away from the area 29 a distance equal to the desired tray depth, a scored fold line 33 spans the blank between the incised sections 17 to demark a tray end panel 34 foldable on the line 28 into perpendicular relation with the area 29, and paralleling said line 33 at the junctions of the scored line sections 18 and incised sections 19

a scored fold line 35 is spaced from the line 33 a distance approximately one-half the length of the area 29 to delimit a tray cover area 36 disposable, by virtue of the fold lines 28 and 33, 5 to spacedly overlie the adjacent half portion of the area 29, extensions of said scored line 35 as incisions 37 laterally across the blank side strips functioning to cut away corners of the otherwise rectangular blank and to complete the definition of flaps 38 constituted from ends of the blank side strips and outstanding laterally of the blank from ends of the area 36 for folding into perpendicular relation with said area 36 10 and to foldably associate said panel 40 with the scored line sections 18. Paralleling the fold line 35 in a spacing outwardly therefrom corresponding with the desired tray depth, a scored fold line 39 spans between the incised sections 19 to define a panel 40 conformed to the panel 34 and to foldably associate said panel 40 with a narrow end strip 41 laterally of and terminating the blank. At approximately the midlength of each scored line section 16 and laterally of each side strip panel 30, a short slit 42 intersects the panel material to extend from the line section 16 to about the midwidth of the panel, and from the outer end of each of said slits 42 a further cut 43 is formed through the panel material to spacedly parallel the adjacent line section 16 in a length away from the slit where 15 20 with it joins and toward the flap 32 at the same side of the blank a distance slightly exceeding the flap 38 dimension longitudinally of the blank, whereby said slits 42 are conditioned to receive and cooperate with the tabs 26 and the cuts 43 25 30 35 are arranged to pass free ends of the flaps 38 when the blank is manipulated into usable tray form. Completing the blank for its intended use, circular apertures 44 are spaced apart laterally of and to open through the cover area 36 in a size and arrangement accommodative of beverage containers, such as cups, bottles, and the like, relatively-foldable, angularly-spaced fingers 45 of the area 36 material preferably being retained in inward projection radially of 40 45 each aperture 44 to facilitate reception and retention therein of different size containers, and holes 46 are cut through the area 29 in a size smaller than the apertures 44 in such disposition as to register their centers with those of the 45 50 55 apertures 44 when the tray is erected to its form of practical use, said holes 46 serving to accommodate tapered extensions of products, such as ice cream cones, and thereby facilitate and secure such products in supported relation with in and through said apertures.

The sheet blanks constituted as shown and above described include every element of the trays they are designed to provide, hence each such blank represents and is a completed tray 60 unit, in so far as manufacture is concerned, and is in condition for sale, storage, and transportation in its sheet form, needing only simple and brief manipulation to convert it into usable tray form. The manipulations required for erection 65 of the tray into form for use may vary somewhat as to sequence, but are, obviously, essentially as follows. The flaps 27 and 32 are folded on the lines 22 and 28 into perpendicular relation with the plane of the sheet; the side panels 30 are 70 then folded on the line sections 16 into perpendicular relation with the sheet to dispose the associated flaps 27 and 32 transversely across and above the sheet with the flap ends of each pair in opposition; the end panel 25, with the panel 26, is folded on the line 22 upwardly and

exteriorly across the flaps 21 and the panel 26 is then folded on the line 24 downwardly and interiorly across said flaps to engagement of its tabs 21 in the slits 23, thus completing and securing one end of the tray; the panel 34 carrying the area 36, panel 40, strip 41 and flaps 38 is then folded on the line 28 upwardly and exteriorly across the flaps 32, the flaps 38 are folded on their line sections 18 inwardly toward the tray and to engage the outer sides of the side panels 30, the area 36 is folded on the line 33 to close over the adjacent portion of the area 29 and free ends of the flaps 38 are entered in and through the cuts 43 as the area 36 is urged into engagement with free edge margins of the side panels 30; and finally the panel 40 is folded on the line 35 to bridge in end engagement with and between midlengths of the side panels 30 and is urged into spaced parallelism with the panel 34 closing one end of the tray, such urging of the panel 40 into its upstanding relation with and centrally across the area 29 operating to engage the tabs 20 in the slits 42 and to fold the strip 41 on the line 39 against and in overlying relation with the central transverse zone of the area 29, thus completing the tray ready for use with a half-area, open-top compartment, a half-area, boxed section to which the apertures 44 open, and with the interfolded tray elements locked against inadvertent separation.

The alternative embodiment of the invention shown in Figures 6-10, inclusive, of the drawings is but an adaptation and extension of the construction hereinabove described to the production of a tray characterized by boxed ends, each arranged for the accommodation of beverage containers, at either side of and defining an open-top compartment, thus to enlarge the tray capacity in a form and style convenient for the simultaneous serving of up to four customers. As in the case of the embodiment first described, the modified or alternative form of the invention is produced as an initially-flat, generally-rectangular, sheet blank appropriately worked and patterned for manipulation and interfolding of its elements to constitute the desired tray ready for use, the blank of the modified embodiment of the invention differing only in proportion and arrangement of its elements from the blank shown in Figure 5 and hereinabove described. Symmetrical with respect to its transverse median line, the blank represented by Figure 10 is longer in proportion to its width than the blank of Figure 5 and is formed with duplicate end portions, each of which corresponds to the box-forming arrangement of elements as shown at the upper end of the latter view. Thus, in the blank of the modified embodiment, Figure 10, the flaps 32 and 38, the panels 34 and 40, the strip 41, the cover area 36 with its apertures 44, and the tabs 20 are interrelated and associated with the central area and side strip portions of the blank by means of the scored fold line 28 in the identical structural and functional arrangement hereinabove detailed, while at the other end of the blank according to Figure 10 a duplicate arrangement of flaps 32' and 38', panels 34' and 40', strip 41', cover area 36' with apertures 44', and tabs 20' is substituted for the flaps 27 and panels 25 and 26 of the Figure 5 showing in outward extension from the blank central area and side strip portions beyond the scored fold line 22' paralleling the line 28. To provide an adequate open-top compartment between the boxed ends of the alternative tray embodiment, the tray

bottom area 29 of Figure 5 is extended in length to provide the rectangular central area 29' of Figure 10 and the side strips 30 of Figure 5 are correspondingly lengthened to form the substitute strips 30' of the modification, said area 29' having the holes 46 adjacent one of its ends as previously described and a duplicate arrangement of like holes 46' adjacent its other end, while the strips 30' have the slits 42 and cuts 43 in the disposition and for the purposes previously set forth and a duplicate arrangement of slits 42' and cuts 43' disposed for coaction with the tabs 20' and flaps 38'. Obviously, elements constituting the end portions of the blank as shown in Figure 10 may be interfolded and interlocked in the manner heretofore explained to develop the tray form shown in Figures 6, 7, 8 and 9 wherein both ends of the tray are boxed and conditioned for reception and support of beverage containers, or the like, and an open-top compartment for the reception of solid foods is defined between said boxed ends in an assembly adequate for the serving of four customers.

As is clearly apparent, the improvement, in either of its illustrated embodiments, is conservative of stock material, simple and economical of production, convenient of storage, handling and shipment, simple of manipulation into form for practical use, and well adapted to the variations of purpose and use for which it is designed, the low-cost features characterizing the improvement favoring its use in situations and under conditions where salvage of the used trays is infeasible.

Since changes, variations, and modifications in the form, construction, and arrangement of the elements shown and described may be had without departing from the spirit of our invention, we wish to be understood as being limited solely by the scope of the appended claims, rather than by any details of the illustrative showing and foregoing description.

We claim as our invention:

1. A serving tray comprising, in a unitary, self-locked, interfolded assembly, a rectangular tray bottom member, like side strip panels integrally and foldably upstanding perpendicularly from and along opposite edge margins of said bottom member, foldably-related and extensions of said panels aligned to traverse opposite ends of said bottom member in perpendicular relation with said member and panels, a foldably-related end extension of said bottom member transversely scored as a succession of contiguous rectangular areas whereof the innermost upstands perpendicularly from the bottom member as a tray end closure exteriorly and upwardly across the adjacent side strip panel end extensions, the next outward of the areas spans between upper margins of the side strip panels to spacedly parallel the bottom member as a cover for a portion thereof, the next adjoining of the areas spans between the side strip panels to edge-close against the bottom member in spaced parallelism with said end closure areas as a partition transversely of the tray, tabs projecting from opposite ends of said partition area through slits intersecting the side strip panels, foldably-related flaps on opposite margins of said cover area exteriorly embracing the side strip panels in end engagement with said bottom member and edge-abutting relation with ends of said partition area through slits intersecting said panels perpendicular to and intersecting corresponding ends of the tab-accommodating slits, container-seating apertures intersecting said cover area, a

terminal strip on said bottom member end extension foldably and perpendicularly related to said partition area in surface engagement against said bottom member to stiffen said partition area against flexure, a transversely-scored extension foldably related with the other end of the bottom member to upstand perpendicularly therefrom upwardly and exteriorly and then downwardly and interiorly across the adjacent side strip panel end extensions, and tabs projecting from the free end margin of said transversely-scored extension in engagement through slits at the corresponding end of the bottom member.

2. A serving tray comprising, in a unitary, self-locked, interfolded assembly, a rectangular tray bottom member, like side strip panels integrally and foldably upstanding perpendicularly from and along opposite edge margins of said bottom member, foldably-related end extensions of said panels aligned to traverse opposite ends of said bottom member in perpendicular relation with said member and panels, a foldably-related end extension of said bottom member, on each end of said bottom member, transversely scored as a succession of contiguous rectangular areas, each of said bottom member end extensions having an innermost area upstanding perpendicularly from the bottom member as a tray end closure exteriorly and upwardly across the adjacent side strip panel end extensions, a next outward area spanning between upper margins of the side strip panels to spacedly parallel the bottom member as a cover for a portion thereof, a next adjoining area spanning between the side strip panels to edge-close against the bottom member in spaced parallelism with said end closure area as a partition transversely of the tray, tabs projecting from opposite ends of said partition area through slits intersecting the side strip panels, foldably-related flaps on opposite margins of said cover area exteriorly embracing the side strip panels in end engagement with said bottom member and edge-abutting relation with ends of said partition area through slits intersecting said panels perpendicular to and intersecting corresponding ends of the tab-accommodating slits, container-seating apertures intersecting said cover area, and a terminal strip foldably and perpendicularly related to said partition area in surface engagement against said bottom member to stiffen the associated partition area against flexure.

3. In a serving tray having a rectangular tray bottom member, like side strip panels integrally and foldably upstanding perpendicularly from and along opposite edge margins of said bottom member, and foldably-related end extensions of said panels aligned to traverse opposite ends of said bottom member in perpendicular relation with said member and panels, means interfoldably coacting with said bottom member, side strip panels, and panel end extensions to define a boxed tray end closure adapted for the reception and support of beverage containers, said means comprising a foldably-related, integral extension from and coextensive in width with the bottom member end, spacedly-parallel scorings transversely of said extension to define a succession of contiguous rectangular areas thereon in a manner to constitute the innermost said area as a tray end closure upstanding perpendicularly from the bottom member ex-

teriorly and upwardly across the adjacent side strip panel end extensions, the next outward area as a cover spacedly paralleling and overlying a portion of the bottom member in spanning relation between upper margins of the side strip panels, the next adjacent area as a partition transversely of the tray between the side strip panels edge-closing against the bottom member in spaced parallelism with said end closure, and the terminal area as a strip foldably and perpendicularly related to said partition in surface engagement against said bottom member, tabs projecting from opposite ends of said partition through slits intersecting the side strip panels, container-seating apertures intersecting said cover, and foldably-related flaps on opposite margins of said cover exteriorly embracing the side strip panels in end engagement with said bottom member and edge-abutting relation with ends of said partition through slits intersecting said panels perpendicular to and intersecting corresponding ends of the tab-accommodating slits.

4. In a serving tray constituted as a rectangular paperboard box having a bottom member, end walls, and side walls hingedly connected to the bottom member and formed with at least one covered end compartment and an open top compartment adjacent thereto, a foldably-related flap extension of the covered compartment top closure perpendicular to the box bottom as a partition between said compartments, and container-seating apertures intersecting the covered compartment top closure, an interlock between said covered compartment top closure, flap extension, and the side walls of the box effective to stiffen the flap-constituted partition against shift and flexure and to condition said top closure for support of a charge, said interlock comprising slits transversely of the box side walls registered with the ends of the flap-constituted partition, tabs outstanding from the ends of the flap-constituted partition through said slits, foldably-related flaps oppositely outstanding from side margins of said top closure in a length equal to the box depth, said flaps joining the top closure on a line extending from the fold line of said flap extension to approximately the mid-width of the top closure, and slits extending longitudinally of the box sides from corresponding ends of the tab-accommodating slits for the reception of said flaps when the latter are folded into perpendicular relation with the top closure, whereby to dispose said flaps in end engagement with the box bottom and edge-abutting relation with ends of the flap-constituted partition; together with a foldably-related flap along the otherwise free edge of the flap-constituted partition adjacently overlying the box bottom.

EARL P. BUCHMILLER.
